UNITED STATES PATENT OFFICE.

GEORGE E. SHIELDS, OF LOS ANGELES, CALIFORNIA, ASSIGNOR OF ONE-FOURTH TO HAROLD E. SHYER, ONE-FOURTH TO JAMES P. BERNE, AND ONE-FOURTH TO LOYD E. WRIGHT, ALL OF LOS ANGELES, CALIFORNIA.

CARBURETER ATTACHMENT.

1,347,297.

Specification of Letters Patent. Patented July 20, 1920.

Application filed June 24, 1919. Serial No. 306,470.

To all whom it may concern:

Be it known that I, GEORGE F. SHIELDS, a citizen of the United States, residing at Los Angeles, county of Los Angeles, and State of California, have invented a certain new and useful Carbureter Attachment, of which the following is a specification.

My invention relates to carburizing means for internal combustion engines, and has particular reference to an auxiliary or supplementary attachment co-acting with a carbureter and combustion engine, for utilizing the warm air, gases and vapors accumulating in the crank case during the operation of the engine.

One of the objects of this invention is to provide a simple and efficient device that may constitute an attachable complement to, or form an integral part of, a carbureter and by which the gas content of a crank case, with the proper admixture of air, may be drawn into and through the carbureter, thereby assisting in keeping cool the engine, preheating and more extensively vaporizing the carbureter mixture and enriching the same.

Other objects will appear from the subjoined specification, in connection with the accompanying drawing, which represents one form of embodiment of my invention, and in which—

Figure 1 is a side view of a carbureter of known construction, partly broken, and a sectional view of my invention in conjunction therewith, and

Fig. 2 is a reduced plan view of my invention.

Generally considered, my invention comprises a supplemental mixing chamber in communication with the main mixing chamber of a gas engine carbureter, and a means of connection between said supplemental mixing chamber and the crank case of an engine, whereby the vaporous accumulations in the crank case may be drawn into the mixing chamber of the carbureter where it commingles with the main fuel charge prior to its induction into the engine.

Referring to the drawing, one form of a carbureter of known construction may comprise an air passage 1; a mixing chamber 2; and a fuel supply 3, with the various other appurtenances essential to its operation.

Specifically my invention comprises a,

chamber 4, formed with an annulus 5, which is held in position upon the walls of the mixing chamber 2, by a cap 6, or in any other substantial manner. Communication between the chamber 4 and the annulus 5, is established by a passageway 7. Screwed into and constituting a part of the chamber 4, is a fitting 8, in the top of which is seated a ball 9, forming a valve for opening and closing the duct 10, in said fitting, and respectively permitting the intake of the vaporous mixtures and preventing back flow of the charge in the mixing chamber 2. This fitting 8 is provided on one side with a constricted opening 11, through which atmospheric air may be drawn, and on the other side with a pipe 12, connecting the duct 10 with a breathing pipe 13 of a combustion engine, or directly with the crank case 14.

In operation, the vacuum produced in the mixing chamber 2, by the piston or pistons on the intake strokes, is extended through the passageway 7 in the annulus 5, to the chamber 4. This force lifts the ball from its seat on the duct 10, and draws from the crank case 14, through the pipe 12 and fitting 8, a charge of air and vaporous constituents that may have become volatilized by the heat generated by the engine. Concurrently with the inrush of the crank case air, atmospheric air is taken in through the constricted opening 11, in quantities sufficient for an explosive mixture. This supplemental charge then enters the main mixing chamber 2 and commingles with the main fuel charge of the carbureter.

In practice I have found that the crank case of a combustion engine, during operation, contains considerable quantities of warm vaporous or gaseous substances, heretofore permitted to go to waste, and that the efficient utilization of the contents of a crank case in the manner herein set out, results in a decided economy in, and better gasification, of the fuel.

Obviously, the withdrawal of part or all of the heated or vaporized fluid from the crank case is followed by replacement with fresh air, and hence a constant and beneficial cooling is effected.

What I claim, is:

1. An attachment for carbureters comprising in combination with the main mixing chamber thereof, an annulus arranged

to fit upon the top of said mixing chamber, a cap for securing said annulus upon said chamber, said annulus formed with a chamber extended outside of and free of the mixing chamber and formed with a horizontal passageway connecting said mixing chamber with the chamber of said annulus, a fitting connecting with said last named chamber having an inlet, and a valve in said chamber.

2. An attachment for carburetors comprising in combination with the main mixing chamber thereof, a hollow body free of said

mixing chamber, said hollow body formed with an annulus arranged to seat upon the top of the mixing chamber and provided with a horizontal passageway connecting the main mixing chamber with said hollow body, means to secure the annulus upon the top of the mixing chamber, a fitting connected with said hollow body having a passageway communicating with the atmosphere, a valve in said passageway, and a connection between said fitting and the crank case of an engine.

In testimony whereof I have set my hand. 25
GEORGE F. SHIELDS.
